UNITED STATES PATENT OFFICE.

CHARLES JACOBSON, OF WARREN, PENNSYLVANIA.

GAS-ENGINE.

No. 861,729.

Specification of Letters Patent.

Patented July 30, 1907.

Application filed July 16, 1904. Serial No. 216,674

To all whom it may concern:

Be it known that I, CHARLES JACOBSON, a citizen of the United States, residing at Warren, in the county of Warren and State of Pennsylvania, have invented 5 new and useful Improvements in Gas-Engines, of which the following is a specification.

My invention relates to certain new and useful improvements in gas engines and particularly to that class of engines which is characterized as the hit-and-miss type; and my invention consists of the parts 10 and the constructions, arrangements and combinations of parts which I will hereinafter describe and claim.

In the accompanying drawing forming part of this specification and in which similar letters of reference 15 indicate like parts in the several views,—the figure represents a longitudinal elevation view, partly in section, of an engine cylinder and portion of a bed plate, showing the internal bushing and the manner in which it is secured in place.

20 In carrying out my invention I may employ the salient features thereof in connection with an engine of the hit-and-miss type or with any of the usual types of explosive engines without any departure from the spirit of my invention.

25 In the drawing, I illustrate an engine of the horizontal cylinder type whose cylinder is appropriately secured to a bed-plate C of any suitable and desired design and construction and which cylinder comprises, essentially, a readily removable bushing A which is first put loosely in place and is then rigidly 30 secured to the bed-plate to thereby form an inner liner for the cylinder.

The exterior of the cylinder is formed by a water 35 jacket shell B in which water is caused to circulate by any of the well known methods in use, or in any appropriate manner to effect the cooling of the cylinder.

The cylinder bushing is designed to be fitted endwise against a shoulder or seat A' formed in or on the water jacket shell while an annular flange A'' formed 40 on the bushing is designed to accurately circumferentially fit the open outer end of the jacket shell B and to fit flatwise against a corresponding vertical face 10 of the engine bed-plate, as shown in the figure.

Between the vertical meeting faces of the annular 45 flange A'' and bed plate, and between the inner end of the bushing and the seat formed by shoulder or channel A' formed in or on the water jacket, are placed appropriate packings which are designed to render the joints at the aforesaid places water tight. 50 Thus the joint between the water jacket shell B and the end of the bushing at A', the joint between the bushing and the bed plate, and the joint between the water jacket shell and the bed plate are all packed with some appropriate packing to make these joints

secure against leakage; and as the packing at the 55 first-named point must also stand the explosive force of the charge the importance of properly securing the same will be manifest. This latter packing and in fact the packings between the shell and bushing and the bed plate, are secured firmly and effectively in 60 place by clamping together the water jacket shell, the bushing, and the bed plate, and this object is obtained by the use of the studs D and nuts, or other equivalent or appropriate means.

By channeling or countersinking the inner end of 65 the water jacket shell to form the aforesaid seat or shoulder, and the placing of the packing upon this shoulder and seating the bushing endwise thereon, I am enabled to obtain an especially effective joint, this being largely the result of the shape of the joint and 70 the manner of seating the bushing, which make it practically impossible for the gases to be blown around the square corner of the fit between the shell and the end of the bushing.

The cylinder is provided with the valve chest D' 75 to which the explosive charge is admitted through the inlet valve J, from which chest the spent products of combustion are delivered by an exhaust valve and actuating mechanism.

Having thus described my invention what I claim 80 as new and desire to secure by Letters Patent is,—

1. In an explosive engine, the combination of the bed 85 plate having a vertical flange forming a bearing face, a water jacket shell having a flange abutting squarely against the face of the bed plate, said shell having an annular shoulder or seat formed on the inner face of its opposite end, and a removable bushing interior of the shell having one end to abut endwise against the said inner shoulder of the shell and having its opposite end provided with an outwardly extending flange the outer face of 90 which seats against the face of the bed plate while the periphery of the flange abuts edgewise against the adjacent inner surface of the water jacket shell.

2. An improved explosive engine having in combination a bed plate with an outwardly projecting flange forming a bearing face, a water jacket shell having at one end a flange forming a bearing face to abut the face of the bed plate, said shell having an inner wall at the opposite end provided with an annular shoulder, a bushing within the shell having one end seated against the annular shoulder 100 of the shell and having the other end passed through the flanged face of the base plate, said bushing having also, an annular flange intermediate of its ends adapted to bear flatwise against the bearing face of the bed plate and edge-wise against the inner wall of the adjacent end of the water jacket shell, and longitudinally extending bolts by 105 which the parts are held in an immovable position.

In testimony whereof I have hereunto set my hand in presence of two subscribing witnesses.

CHARLES JACOBSON.
